PASTE-APPLYING MECHANISM

William A. Brown, Bronx, N. Y., assignor, by
mesne assignments, to Hartford-Empire Com-
pany, Hartford, Conn., a corporation of Dela-
ware

Application January 5, 1945, Serial No. 571,512

10 Claims. (Cl. 91—54)

1

This invention relates to mechanism for applying paste or other suitable adhesive to sheets or strips or the like, such, for example, as labels, to aid in securing them to articles such as cans, bottles, and similar containers or articles.

In applying labels to such articles they are usually caused to roll along a trackway, either horizontal or vertical, a stack of labels being presented to the trackway from beneath it or at one side of it. The front end of the foremost label is picked up by adhesive applied to the article and as the rolling of the article continues the label is wrapped about it. In order to secure the rear or lap end of the label to the article it is necessary to apply additional adhesive to this end of the label.

The adhesive for the lap end pasting of the labels is usually applied by means of an endless belt supported on pulleys, one on either side of the trackway and so arranged as to cause one reach of the belt to sweep across the width of the foremost or uppermost label of the stack near the rear end. A film of adhesive is applied to the belt and deposited thereby in a narrow band extending across the label. Difficulty has heretofore been experienced in preventing a surplus of adhesive from gathering at the side of the label where the belt first comes in contact with it and which tends to spread over the side of the stack and cause the labels to adhere to each other. This interferes with proper feeding of the labels one at a time from the stack and also may disfigure the labels. Furthermore, if such a collection of adhesive is permitted an unsanitary condition will develop in the operation of the labeling machine.

The present invention aims to overcome these difficulties and particularly to eliminate the possibility of the collection of adhesive at either side of the foremost label or of the label stack.

Another object of the invention is to provide a mechanism which will apply the paste in such a way as to avoid any tendency of the paste applying mechanism to shift the labels near the top of the stack sidewise in either direction, which movement would result in the labels being improperly applied to the articles.

The natural shape which labels of different kinds assume in a stack varies. Some labels remain flat while others bulge at the center or curl up at the edges, due to the printing or embossing, so that the paste has to be applied either to a convex or to a concave surface. Another object of the invention, therefore, is to provide mechanism which will apply paste to such labels

2

substantially as readily as it will to flat surfaces.

A further object of the invention is to provide a paste applying mechanism which is simple in construction, easily adjusted, and which will operate with a minimum of attention.

The invention will be described in connection with a mechanism for applying labels to round articles, such as cans, but only a sufficient portion 10 of the label applying mechanism will be illustrated to show the general principle of its operation. It will be understood that the device of the present invention can be utilized wherever it is desired to apply a relatively narrow elongated band of adhesive across the surface of a flat, concave, or convex sheet.

The embodiment of the invention in a can labeling machine is shown in the accompanying drawings, wherein

20 Fig. 1 is a side elevation of the paste applying mechanism with certain parts shown in section, the entire view being also a section taken transversely of the labeling machine and through a stack of labels on the broken line 1—1 of Fig. 2;

25 Fig. 2 is a plan view of the paste applying mechanism and the rear portion of the label stack with parts broken away;

30 Fig. 3 is a fragmentary and somewhat dia-
grammatic longitudinal section through a part of the labeling machine and the stack of labels, the section being taken on line 3—3 of Fig. 1;

35 Fig. 4 is a fragmentary perspective view showing the manner of applying paste to the uppermost label; and

Fig. 5 is a fragmentary plan view showing the rear or lap end of a label with the paste applied thereto.

40 Referring now to the accompanying drawings, and first to Fig. 3, the cans, one of which is shown in two different positions indicated by numerals 1 and 2, advance through the labeling machine from left to right along the track sections 3 and 4 between guides 4a (Fig. 1), being propelled by the rolling action of the lower reach 5 of a continuously moving belt which is held in frictional contact with the cans by means of stationary rollers 6.

45 Before arriving at position 1, each can is passed in contact with a plurality of rotating disks 7, or other suitable gumming device. Disks 7 are mounted upon a shaft 8, rotate within a body of gum 9 and apply to the sides of the can a plurality of spots of adhesive arranged in

spaced relation throughout the length of the can.

The stack of labels 10, shown in longitudinal vertical section in Fig. 3, is placed at such distance from the gum applying disks 7 that the can will make one complete revolution in moving from the disks to the front end of the label stack. Hence the spots of adhesive on the can will pick up the front end of the uppermost label and cause it to adhere to the can. Then the can rolls up the inclined portions 11 of rails 4, elevating the can above the top of the stack of labels and separating the uppermost label from the remainder of the stack.

The labels are of such length as to completely surround the can and permit the ends of the labels to overlap each other. In order to secure the rear or lap end of the label in place paste is applied thereto by means of a paste belt, and as the can continues to advance along rails 4 the right-hand or rear end of the label slides out from beneath belt 12 and the belt then contacts the next label of the stack. During this movement of withdrawal the uppermost label, which may be indicated by reference numeral 13, slides beneath a curling bar 14 which is carried by pivoted arms 15 and arranged to press yieldingly against the top of the stack of labels.

Further rolling of the can along the rails 4 completes the wrapping of the label about the can and the can then rolls for a short distance over a resilient mat or pad 16 arranged beyond the ends of rails 4 and by which the weight of the can, as it rolls along, is caused to smooth out the label, removing wrinkles and pressing together the overlapping ends of the label so as to leave it neatly applied to the can.

The paste applying belt 12 is trained around a driving pulley 17 arranged at the left-hand side of the apparatus as viewed in Fig. 1 and around a smaller pulley 18 on the right-hand side of the apparatus. Driving pulley 17 is fixed to a constantly rotating shaft 19 and the lower portion of the pulley dips into a body of paste 20 contained in a receptacle 21 which is fixed by means of brackets 22 to the frame of the labeling machine. Pulley 18 and other parts of the paste applying mechanism are supported upon a rigid horizontal rod 23 which is secured within a clamping device 24 on the side of paste receptacle 21.

Belt 12 is preferably made of metal wire wound into a closely coiled helix, the interstices of which may be varied as to their paste holding capacity by stretching the belt to different extents as set forth in U. S. Patent No. 1,985,293, issued December 25, 1934, to W. D. Kimball, assignor to the same assignee as the present application. However belt 12 may be composed of other material such as rubber, leather, etc.

An adjustable scraping blade 25 is mounted on a support 26 secured to receptacle 21 and is adjustable by means of the knurled nuts 27 to permit more or less paste to be carried by the belt. This blade removes surplus paste which is carried up from the body of paste 20, leaving only a narrow bead 28 (Fig. 2) of paste at the center of the outside of belt 12. As the belt travels from the left to the right in Fig. 1, it may move into contact with an adhesive deflector 29 which shifts this bead of paste around to the bottom of the upper portion 12a of the belt as it leaves the driving pulley 17.

As indicated in Fig. 1, the two sides or reaches of the belt 12 are arranged to cross each other, the upper portion 12a of one reach on the left-

hand side of the label stack becoming the lower portion 12b on the right-hand side and passing onto the lower side of pulley 18. After rounding pulley 18 it becomes the upper portion 12c of the other reach on the right-hand side of the stack and then, after crossing the label stack again, becomes the lower portion 12d and passes over a guide pulley 30, and back to driving pulley 17.

10 The two reaches of the belt are arranged to cross each other and simultaneously to approach the label stack 10 from above and to make contact with the uppermost label 13 of the label stack at a point 12e intermediate the side edges of this label, as shown in Fig. 1. In order to obtain the full advantage of the invention the two reaches of the belt should engage or make contact with each other at the crossing point 12e and this crossing point should be at the center of the label, that is, midway between its side edges. 15 The bead of paste carried forward by the belt after leaving scraper blade 25 and shifted around to the bottom of the left-hand upper portion 12a of the belt by deflector 29 becomes distributed over the lower half of the belt by the time it reaches the crossing point 12e. In fact, when a helical wire belt is employed the deflector 29 can be omitted, because the natural vibration of the 20 spring belt caused by the frictional engagement of the two reaches of the belt at the crossing point 12e produces a shifting of the bead of paste from the outer or upper side of the belt to the lower side and a flattening out of this bead of paste into a thin and more uniform film.

25 As the belt continues its travel towards the right from the crossing point 12e across the upper surface of the right-hand half of the uppermost label, it applies to the label a narrow strip of paste, indicated approximately by numeral 31 in Fig. 5. Similarly the portion 12d sweeps across the left-hand half of the uppermost label and applies thereto a second narrow strip of paste which is indicated approximately by numeral 32 in Fig. 5. As the portion 12a of the paste 30 belt engages portion 12c, that is, the other reach of the belt, at the crossing point 12e, a part of the paste carried by portion 12a is transferred to the other reach and carried to the left by the lower left-hand portion 12d. That is to say, a part 35 of the paste which is applied to the label by the portion 12d of the belt is received directly from the portion 12a at the crossing point 12e. Even if, because of maladjustment of the scraping blade 25, or otherwise, chunks or balls of paste 40 are carried along the portion 12a, such surplus paste is immediately transferred at the crossing point 12e to the portion 12d and returned to the paste receptacle without collecting upon or damaging any label.

45 From the above it will be understood that one reach or side of belt 12 applies the paste to the right-hand portion of the label as viewed in Fig. 1, while the other reach or side of the belt applies the paste to the left-hand side of the label. The 50 paste is thus applied to the label simultaneously by two wiping actions in opposite directions from the center of the label to its side edges. The result is that there is no tendency for the label to shift sidewise in either direction. The upper 55 part of label stack 10 may extend without side support for one-half inch or more above the tops of the stack guides 35 as shown in Fig. 1.

60 As the label is drawn from beneath the paste belt the paste is spread over the surface of the 65 label by the wiping action of the belt from the

paste strips 31 and 32 to the rear end of the label as indicated in Fig. 5.

The reach of the belt which applies the paste to the right-hand portion of the label approaches the label from above and passes over the left-hand edge of the stack 10 at a substantial distance above it. Similarly, the reach which applies the paste to the left-hand portion of the label also approaches from above the stack and crosses the right-hand edge of the top label well above it. Hence there is no opportunity for paste to be scraped off the belt at either side edge of the label stack and run down over its sides. Even labels whose edges are considerably curled by embossing or otherwise will not touch the approaching sides of the paste belt.

The adjustment of the paste belt with respect to the label stack is controlled principally by the adjustment of pulley 18. It may also be controlled by adjusting guide pulley 39 vertically and this pulley may be mounted on a vertically adjustable bracket (not shown). For the purpose of adjusting pulley 18 it is mounted on a supporting bracket 33 which has an adjustable clamp 34 by which it is positioned on supporting rod 23. By means of this support pulley 18 may be tilted in such a way as to cause the two sides of belt 12 to cross at about the center of the label stack; also, the belt may be stretched to a greater or less extent to vary the amount of adhesive carried by it (when a helical spring belt is used).

The paste applying mechanism of the present invention applies the paste to labels of different characteristics without the use of a center finger and without danger of smearing the paste on either edge of the label stack. It eliminates the need for shoes and other devices to prevent such smearing heretofore employed where the paste was applied to the label by one side or reach only of the belt, and does away with the annoyance accompanying the adjustment of such devices. The present paste applying mechanism is simple to adjust and requires little service attention.

It will be understood that the embodiment of the invention illustrated and described above exemplifies the nature of the invention but does not limit it, and that changes may be made without exceeding the scope of the invention which extends to such constructions as are included within the terms of the appended claims.

I claim:

1. In a lap end pasting mechanism for labeling machines, means for supporting a stack of labels, an endless belt adapted to carry adhesive and arranged to travel crosswise of said stack, means for driving said belt, means for supplying adhesive thereto, and guides for directing oppositely moving portions of said belt into contact with each other and with the foremost label of the stack intermediate its edges and causing the contact of each of said belt portions with the label to continue to the opposite edges of the label.

2. In a lap end pasting mechanism for labeling machines, means for supporting a stack of labels, an endless belt adapted to carry adhesive and arranged to travel crosswise of said stack, means for driving said belt, means for supplying adhesive thereto, and guides for directing oppositely moving portions of said belt into contact with each other and with the foremost label of the stack substantially midway between its side edges and causing the contact

of each of said belt portions with the label to continue to the opposite edges of the label.

3. In a lap end pasting mechanism for labeling machines, means for supporting a stack of labels, an endless belt adapted to carry adhesive and arranged to travel crosswise of said stack, means for driving said belt, means for supplying adhesive thereto, and a guide for directing one reach of said belt into contact with the foremost label of the stack intermediate the edges thereof and causing it to sweep along the label surface to one of its edges, and a second guide for directing the other reach of said belt into contact with said first mentioned reach and into contact with the label at a point contiguous to that at which the first reach contacts the label and causing it to sweep along the label surface to the opposite edge thereof.

4. In a lap end pasting mechanism for labeling machines, means for supporting a stack of labels, an endless belt adapted to carry adhesive and arranged to travel crosswise of said stack, means for driving said belt, means for supplying adhesive thereto, and a guide for directing one reach of said belt into contact with the foremost label of the stack at a point midway between the edges thereof and causing it to sweep along the label surface to one of its edges, and a second guide for directing the other reach of said belt into contact with the label midway between its edges and causing it to sweep along the label surface.

5. In a lap end pasting mechanism for labeling machines, means for supporting a stack of labels, an endless belt adapted to carry adhesive and arranged to travel crosswise of said stack, means for driving said belt, means for supplying adhesive thereto, and means for directing oppositely moving portions of said belt into contact with the foremost label of the stack intermediate its edges comprising, guide means for the respective reaches of said belt disposed at one side of the label stack, one outwardly and one inwardly of the outermost label, a pulley disposed on the opposite side of said stack at about the level of said label, and means for adjustably supporting the same with its axis tilted with respect to said label surface, the reaches of the belt extending over said guide means and around said pulley and crossing each other.

6. In a machine for applying adhesive to the surface of a sheet, means for supporting the sheet, an endless belt adapted to carry adhesive, means for driving the same, means for applying adhesive thereto, and guides for directing the two reaches of said belt into contact with each other and with said sheet intermediate the edges thereof to apply adhesive thereto simultaneously.

7. In a lap end pasting mechanism for labeling machines, means for supporting a stack of labels, an endless belt adapted to carry adhesive, means for driving the same, means for supplying adhesive thereto, and means for supporting said belt to travel crosswise of said stack with the two reaches of said belt crossing each other intermediate the side edges of the foremost label and contacting the same to apply adhesive thereto simultaneously.

8. In a lap end pasting mechanism for labeling machines, means for supporting a stack of labels, an endless belt adapted to carry adhesive, means for driving the same, means for supplying adhesive thereto, and supports for said belt directing it to travel crosswise of said stack with the two

reaches of said belt crossing in contact with each other intermediate the side edges of the foremost label of said stack and contacting the same to apply adhesive thereto simultaneously.

9. In a lap end pasting mechanism for labeling machines, means for supporting a stack of labels, an endless belt adapted to carry adhesive, means for driving the same, means for supplying adhesive thereto, and supports for said belt directing it to travel crosswise of said stack with the two reaches of said belt crossing in contact with each other substantially midway between the side edges of the foremost label of said stack and contacting the same to apply adhesive thereto simultaneously.

10. In a lap end pasting mechanism for labeling machines, means for supporting a stack of labels, an endless belt adapted to carry adhesive and arranged to travel crosswise of said stack, means for driving said belt, means disposed at one side of said stack for supplying adhesive to said belt, means for supporting said belt so that

the reaches thereof cross one another and for directing one reach from said adhesive supplying means directly into contact with the foremost label of the stack, said adhesive applying means including means for supplying a surplus of adhesive to said belt and means for removing said surplus leaving adhesive principally on the outside of the belt, and a deflector engaging the belt and adapted to shift said adhesive to the inside of said belt before the belt contacts the label.
